[57] ABSTRACT

A reciprocating yarn guide having a variable path comprising a carriage which is driven with a reciprocating movement, at least three pulleys mounted on the carriage, at least one belt tensioned around these pulleys, a yarn guide attached to the belt, a position member attached to the belt, and a position adjusting member, the position member being slidably attached to the position adjusting member.

FIG. 1

FIG. 2

FIG. 3

FIG. 4

RECIPROCATING YARN GUIDE

BACKGROUND OF THE INVENTION

This invention relates to a variable path reciprocating yarn guide. More particularly, this invention relates to a reciprocating yarn guide wherein the variable path of the guide may be easily and quickly varied.

Variable path reciprocating devices are utilized in a great number of industries and especially in the textile industry for guiding a yarn to be wound up on a suitable support. These variable path devices basically comprise a linear reciprocating carriage having two arms projecting from the carriage at right angles to each other. One of the arms has the yarn guide attached to it, while the other arm engages a position adjusting bar which may be variable inclined or adjusted. These position adjusting bars are often called "sine" bars since they cause the path of travel to vary. Using these type of position adjusting yarn guide devices, the yarn describes a partial arc of a circle which is not completely satisfactory for the proper formation of a wind up coil.

Generally, these oscillating arc-like devices cause variations in the yarn wind up width or angle if the yarn is either parallel to the direction of the pivoting plane or perpendicular to the pivoting plane.

It has further been suggested that, instead of the one arm being attached directly to the yarn guide, the end should be attached to or control a slide block which, in turn, is attached to the yarn guide. Although this variation translates the partial arc into a linear motion, the utilization of these various devices produces excessive play which, in turn, produces bulges at the ends of the coil especially wherein a coil having a fine pitch is being wound. These bulges are not only unsightly, but they also cause the coil to break down and form tangles upon unwinding.

BRIEF DESCRIPTION AND OBJECTS OF THE INVENTION

It is within the above environment and background that the apparatus of the present invention was developed. Briefly, such apparatus comprises a carriage, means for driving the carriage in a reciprocating motion, at least three pulleys mounted on the carriage, at least one belt mounted on these three pulleys, a yarn guide attached to the belt, a position member attached to the belt and a movable position adjusting bar, the positioning member being slidably attached to the movable position adjusting bar.

It is, therefore, the primary object of the present invention to provide a reciprocating textile winding apparatus wherein the length of the reciprocating path of the guide member can be easily adjusted.

It is a further object of the present invention to provide a reciprocating winding guide which can produce an even coil of various lengths.

It is a still further object of the present invention to provide a winding guide wherein the changes in the path of travel do not affect the configuration of the coil wound on the wind up member.

Still further objects and advantages of the apparatus of the present invention will become more apparent from the following more detailed description thereof.

DETAILED DESCRIPTION OF THE DRAWINGS

The apparatus of the present invention will be more clearly illustrated with reference to the attached drawings wherein:

FIG. 1 is a diagrammatic view of the device in accordance with the present invention;

FIG. 2 is a detailed view of the position adjusting or sine bar; and

FIG. 3 and 4 are diagrammatic views illustrating the operation of the device of the present invention.

FIG. 1 shows a diagrammatic view of the apparatus of the present invention which includes a carriage 1 mounted for reciprocating movement on two parallel guide bars 2 and 3. Carriage 1 is driven in a reciprocating movement by any conventional reciprocating drive 4, such as a motor driven, cam and follower, or link and pin type arrangement. Mounted on carriage 1 are three pulleys 5, 6 and 7. Although three pulleys are shown in

FIG. 1, any number of pulleys greater than three may be utilized as long as at least one pulley is not in line with the other pulleys. Furthermore, it is preferred that the three pulleys are spaced so that the distance between pulleys 5 and 6 and between pulleys 6 and 7 are approximately equal. Stretched around pulleys 5, 6 and 7 is a belt 8 which can be any inextensible or non-stretchable flexible belt. A suitable pulley belt is one made from a fabric reinforced rubber. Belt 8 may either be smooth or may have a series of notches. When

belt 8 is notched, each of pulleys 5, 6 and 7 have a series of lugs, each lug being separated corresponding to the spacing between the notches in belt 8. Also one of the pulleys, especially pulley 7 may be adjustable so that the tension on belt 8 may be changed. This adjustment may be effected by any conventional arrangement. For example, the pulley 7 may be mounted in a slot 20 formed in the frame 1, in which an adjustment screw 21 disposed to move normal to the axis of the pulley 7 is threaded. Upon advancing the screw toward

the axis of the pulley 7, tension in the belt 8 is increased. Upon backing the screw 21 away from the axis of the pulley 7, tension in the belt 8 is decreased.

Mounted on carriage 1 parallel to guide bars 2 and 3 is an additional guide bar 9. Mounted on guide bar 9 is a yarn guide block 10 having a guide member or nip 11 attached thereto. Yarn guide block 10 is also firmly attached to belt 8 so that any displacement of belt 8 also displaces yarn guide block 10.

Also mounted on carriage 1 in a direction perpendicular to guide bars 2 and 3 is a slotted guide member 12. Slotted guide member 12 has an elongated slot 13 perpendicular to guide members 2 and 3. The path of travel of belt 8 between pulleys 6 and 7 is parallel to the sides of slot 13 and is roughly intermediate the sides of slot 13. Attached to belt 8 between pulleys 6 and 7 and projecting through slot 13 is a position member 14. As with yarn guide block 10, position member 14 is firmly fixed to belt 8 so that any movement of belt 8 is reflected in position member 14 and vice versa. The upper end of position member 14 sits within channel position adjusting bar 15. Slidably mounted within the position adjusting bar 15 is a slide member 16 which facilitates the sliding movement of position member 14 within position adjusting bar 15. Bar 15 is mounted on the wind up apparatus by means of a pivot point 17 so that bar 15 may be positioned at any angle relative to guide bars 2 and 3.

FIG. 2 which is an underside view of position adjusting bar 15 shows the construction of slide member 16 within a generally U-shaped channel 18. Although slide member 16 may be merely placed within channel 18, slide member 16 may also be partially held in place by two parallel ribs on each side of channel 18.

FIGS. 3 and 4 show the apparatus of the present invention in use and demonstrate how the variation in the angle or inclination of position adjusting bar 15 affects the length of the path of travel of yarn guide block 10.

In each of FIGS. 3 and 4, the distance between position member 14 at the start and finish of each reciprocal movement wherein the finish positions is indicated by primed numbers, remains constant and is indicated at L_0 . When position bar 15 is set at an angle as shown in FIG. 3, the distance between yarn guide block 10 at the start and finish of the reciprocal movement is indicated as L_1 . In other words, carriage 1 in moving from start to finish, travels a distance of L_0 ; however, yarn guide block 10 only travels a distance of L_1 , less than the entire path of travel of the yarn carriage. Similarly, in FIG. 4 which shows position bar 15 disposed as a different angle of inclination, the distance L_2 which yarn guide block 10 travels is greater than the position or the length of travel L_0 of carriage 1 and position member 14.

Similarly, when bar 15 is disposed parallel to guide bars 2 and 3, the length of travel of yarn guide block 10 will be equal to the length of travel of carriage 1. Accordingly, it can be seen that by varying the angle of

inclination of bar 15 with respect to parallel guide bars 2 and 3, the length of path of travel of yarn guide block 10 can be easily and readily varied and controlled.

While the apparatus of the present invention has been illustrated by way of the foregoing specific embodiments, the same are for the purposes of illustration only and the apparatus of the present invention shall be limited only by way of the following appended claims.

What is claimed is:

1. A reciprocating device having an adjustable path comprising a carriage, means to drive said carriage with a reciprocating movement, at least three pulleys mounted on said carriage, a belt mounted on said pulleys and forming a first run parallel to the direction of movement of said carriage and a second run perpendicular thereto, a yarn guide attached to said first run, a position member attached to said second run, and a position adjusting bar adjustably mounted relative to said carriage, said position member being slidably attached to said position adjusting bar.
2. The apparatus of claim 1 wherein said carriage is mounted on two parallel guide bars.
3. The apparatus of claim 2 wherein said position member is attached to said position adjusting bar by means of a sliding member.
4. The apparatus of claim 1 wherein at least one of said pulleys is adjustable so that the tension of the belt may be varied.
